UNITED STATES PATENT OFFICE

94,548

DESIGN FOR A COMBINATION SMOKER'S ACCESSORY AND HOLDER FOR POKER CHIPS AND THE LIKE

Harry A. Holland, Los Angeles, Calif.

Application October 19, 1934, Serial No. 53,686

Term of patent 7 years

To all whom it may concern:

Be it known that I, Harry A. Holland, a citizen of the United States, residing at Los Angeles, in the county of Los Angeles and State of California, have invented a new, original, and ornamental Design for a Combination Smoker's Accessory and Holder for Poker Chips and the like, of which the following is a specification, reference being had to the accompanying drawing, forming a part thereof:

Fig. 1 is a plan view of the device;

Fig. 2 is a perspective view thereof;

Fig. 3 is a rear elevation thereof;

Fig. 4 is an end elevation taken from the right-hand side of Fig. 1;

Fig. 5 is an end elevation thereof taken from the left-hand side of Fig. 1.

I claim:

The ornamental design for a combination smoker's accessory and holder for poker chips and the like, as shown.

In testimony whereof I have hereunto subscribed my name this 11th day of October 1934.

HARRY A. HOLLAND.
